UNITED STATES PATENT OFFICE.

SOLOMON BOYER, OF GENTRYVILLE, INDIANA.

PLOW.

SPECIFICATION forming part of Letters Patent No. 788,514, dated May 2, 1905.

Application filed October 26, 1904. Serial No. 230,088.

To all whom it may concern:

Be it known that I, SOLOMON BOYER, a citizen of the United States, residing at Gentryville, in the county of Spencer and State of Indiana, have invented certain new and useful Improvements in Plows, of which the following is a specification.

In operating the chilled plow as generally constructed expense, trouble, and vexation are experienced by reason of the point becoming displaced or broken. This is due largely to the fastenings of the moldboard becoming loose and the moldboard working down and displacing the point. The plow-points in common use have a shoulder at the inner or lower side to abut against the toe of the standard and are held to the latter by a single bolt. In operation the fastenings of the moldboard frequently become loose, and as a result the moldboard is borne downward and, pressing upon the plow-point, causes the shoulder to leave the standard, and the whole strain being thrown upon the point approximately in line with the fastening results in its breakage or straining of the parts, so as not unfrequently to require material repairs at the expense of time and money.

The invention is applicable to all kinds of plows—right or left hand, chilled-steel, sulky, gang, walking, or the like—and is particularly intended for all types of chilled plows.

The invention consists of a lug upon the inner side of the moldboard near its lower rear corner to engage over a rear extension of the standard.

For a full description of the invention and the merits thereof and also to acquire a knowledge of the details of construction of the means for effecting the result reference is to be had to the following description and accompanying drawings.

While the invention may be adapted to different forms and conditions by changes in the structure and minor details without departing from the spirit or essential features thereof, still the preferred embodiment thereof is shown in the accompanying drawings, in which—

Figure 1 is a side view of a plow embody-

ing the invention, parts being broken away. 50 Fig. 2 is a perspective view of the standard. Fig. 3 is a perspective view of the moldboard as seen from the inner or rear side. Fig. 4 is a detail transverse section showing more clearly the relation of the lug of the moldboard and the extension of the standard. 55

Corresponding and like parts are referred to in the following description and indicated in all the views of the drawings by the same reference characters. 60

The plow-standard 1 is provided at its lower end with a wing 2 to support the point 2 and moldboard 3, both being secured thereto in the usual manner. The rear extension 4 is straight upon its upper edge and is a trifle 65 longer than shown in standards specially constructed with a view to secure the best results accruing from the invention.

The moldboard 3 has a lug 5 upon its rear side near its lower rear corner. This lug is 70 preferably a part of the moldboard or may be welded or attached thereto in any determinate way. The purpose of the lug 5 is to engage over the rear extension 4 and support the rear part of the moldboard and prevent 75 it from exerting a downward pressure upon the plow-point 2 in the event of the fastenings connecting it with the standard becoming loose. The lug 5 also relieves the moldboard fastenings in a great measure of the 80 strain usually sustained thereby when the plow is in operation. While it is preferred to have the meeting edges of the lug 5 and rear extension 4 square, they may be of any construction to provide an interlocking joint 85 of well-known form, thereby preventing downward displacement of the moldboard even though its fastenings should become loosened to such an extent as under ordinary conditions to permit appreciable downward 90 movement of said moldboard.

Having thus described the invention, what is claimed as new is—

1. In a plow, the combination of a standard having a rear extension, and a moldboard 95 having a lug upon the inner side of its lower rear corner portion to coöperate with the said rear extension and materially relieve the

moldboard of strain and prevent movement of the moldboard in the event of its fastenings becoming loose, substantially as set forth.

2. In a plow, the combination of a standard having a rear extension, and a moldboard provided with an integral lug upon the inner side of its lower rear portion to engage over said rear extension and retain the mold-

board in proper position, substantially as set forth.

In testimony whereof I affix my signature in presence of two witnesses.

SOLOMON BOYER. [L. s.]
